ABSTRACT

A novelty and amusement device comprising a simulated faucet having a suction cup whereby the faucet can be detachably secured to any supporting surface which will retain a suction cup, to present the appearance of a conventional faucet properly supported thereon. The simulated faucet provides a container which may be filled with liquid or the like so that by turning the faucet handle the liquid in the container will flow from the faucet, simulating that of a conventional faucet. The simulated provides an unexpected result when mounted on an unconventional surface such as a dining room or bedroom wall and the above stated turning action is taken.

NOVELTY AND AMUSEMENT FAUCET

BRIEF SUMMARY OF THE INVENTION

One of the objects of this invention is to provide a novelty and amusement device in the form of a simulated faucet provided with a suction cup device whereby it may be detachably secured to a surface to give the appearance of a permanent attachment and in which the faucet can receive a given amount of liquid which is hidden from view, and upon turning the faucet handle the liquid will flow from the faucet in much the same manner that water is discharged from the conventional water faucet. By mounting the simulated faucet on a nonconventional surface, such as a dining room or bedroom wall, or on a filing cabinet door or the like, and filling the faucet with water, which is not visible when in the faucet, an observer will be surprised and entertained when the faucet handle is turned to permit the water or liquid to flow from the spout, simulating the flow from a conventional faucet.

Another object of this invention is to provide a novelty and amusement device which by virtue of its surprise element will afford entertainment.

BRIEF DESCRIPTION OF THE DRAWINGS

In the drawings:

FIG. 1 is a central sectional view of the device shown attached to a supporting surface.

FIG. 2 is a bottom plan view thereof, and

FIG. 3 is an exploded view of the parts forming this device.

The device comprises a hollow faucet body or housing generally indicated by the numeral 10, formed of two identical hollow half sections 12 molded of plastic material, which are united by gluing or bonding along their edges after the operating parts, to be described, are positioned therein. The faucet body or housing is shaped to simulate a faucet and comprises a longitudinal extending hollow portion 14 which merges into a vertically extending hollow portion 16 open at the top and bottom as at 18 and 19, respectively. The rear end of the longitudinal portion is also open as at 20. The vertical portion bulges outwardly at the front as at 22 to simulate that of a faucet.

The bottom open end 19 of the vertical portion is closed by a cap generally indicated at 24 which has an outer annular wall 25 provided with an alignment notch 26 which engages the projection 27 on the exterior of the vertical portion. The outer annular wall 25 has a frictional fit with and surrounds the lower portion of the vertical portion. The cap has a spaced intermediate annular wall 28 provided with a cutout 30. The intermediate annular wall is shorter than the outer wall 25 and defines between it and the outer annular wall an annular space 32. Spaced inwardly of the intermediate annular wall 28 is a short central innermost annular wall 34 which defines between it and the intermediate wall an annular groove 36 for receiving the skirt of a stem, to be described. The bottom of the cap has a bottom wall 38 which is closed, except for a small central opening 39 passing through the axis of the innermost annular wall.

A rotatable stem or spindle generally indicated at 40 is rotatably supported at its lower end inside the intermediate wall 28. The bottom of the stem has an enlarged annular flange 42 from which depends an arcuate-shaped skirt 44 which serves as a valve. The lower end of the skirt is supported within the groove 36. The stem 40 is rotatable so that the arcuate skirt 44 either blocks or unblocks the opening 30. When it blocks the opening the liquid entering the lower cap, particularly the annular space 32 will be prevented from passing through the opening 30 and will remain in the unit. When the stem 40 is rotated so that the open portion adjacent the skirt is aligned with the opening 30 the liquid will pass through the annular space 32 and through the slot opening 30 and through the bottom opening 39 to be discharged from the faucet.

The stem or spindle 40 has an upper annular shoulder 46, and extending upwardly of the shoulder the stem has an annular portion 47, and above that has an end portion which has a

flat side 48. An annular top cap member generally indicated at 50 surrounds the upper portion of the stem to support same. The top cap 50 has an outer annular wall 51 and a spaced shorter inner annular wall 52 with a central opening 53 extending through the annular end wall 54 of the cap. The annular end wall of the cap extends beyond the outer annular wall to provide an annular lip 56. The outer annular wall of the cap fits within the upper open end 18 of the housing and the lip 56 rests on the upper edge of the housing adjacent the opening 18. The upper end of the stem extends through the opening 53, with the flat sided end terminating above the cap 50.

A tear-shaped hollow handle generally indicated at 58 operates the stem 40. The handle has an annular wall 60 which fits over the end of the portion 16 of the faucet. The handle has a boss 62 provided with a recess 63 having a flat wall, which flat wall is aligned with the flat wall 48 at the top of the stem to rotate same.

The rear of the faucet housing has a recessed opening 64. The rear open end 20 of the faucet housing is closed by an end closure generally indicated at 66, comprising an annular vertical end wall 67 and an annular wall 68 having a cutout or opening 69 therein. The closure has a central hub 70 which is internally threaded to receive the metal threaded stem 71

secured to a suction cup 72 which is secured to the closure. Extending rearwardly from the end wall 67 is a plurality of spaced pins 74 which engage the outer wall of the suction cup 72. The annular wall 68 of the end cap is secured inside the open end 20 of the faucet housing with the opening 69 of the closure aligned with the opening 64 on the edge of the housing. The aligned openings 64 and 69 provide an opening for pouring a liquid into the interior of the housing.

A slidable collar generally designated at 80 is slidably supported on the horizontal portion of the housing. The collar when moved to its rearmost position, as shown in section in FIG. 1, serves to hide the openings 64-69 and also to enclose and cover the suction cup 72 when the unit is mounted on a supporting surface.

The unit may be detachably mounted on any supporting surface to which a suction cup may be applied, after which the interior of the housing is filled with a liquid, such as water, through the openings 64-69 by sliding the collar to the dotted line position of FIG. 1. The collar is then slid rearwardly to cover said openings and the suction cup. Before filling the housing or faucet body, the handle 58 is turned so that the skirt 44 of the stem blocks the opening 30 which retains the liquid in the housing. The device is then ready to be operated as an amusement device.

To surprise an unsuspecting person, the handle is rotated to align the skirt opening with the opening 30 and the liquid in the housing and in the cap 24 will flow slowly out of the spout opening 39 simulating a water faucet. To the unsuspecting person the flow of a liquid from a faucet attached to a wall or to an unexpected surface will provide both surprise and amusement.

The parts, except for the suction cup, may be molded of opaque plastic material, preferably polystyrene, and the parts which are exposed to view, such as the faucet body or housing, are vacuum plated with a silver coating to simulate the appearance of an actual water faucet. The opaque housing will prevent anyone from seeing that the faucet is filled with a liquid.

I claim:

1. A novelty device comprising, a simulated faucet having a hollow housing and a hollow discharge nozzle at the front thereof communicating with the interior of the hollow housing and extending downwardly of the housing, said housing having an inlet opening through which a liquid may be manually poured to fill said housing and nozzle with said liquid being retained in said housing and nozzle, said nozzle having an outlet, a vertically supported spindle extending into said hollow nozzle, blocking means at the lower end of said spindle for blocking said nozzle outlet, a handle secured to the top of said spindle and extending above the top of said housing, said han-

idle when manually rotated adapted to rotate the spindle and move said blocking means to unblock the nozzle opening so that the liquid within the housing and nozzle is discharged through said nozzle outlet, and a suction cup at the rear end of said housing whereby said device may be detachably secured to a supporting surface.

2. A device as set forth in claim 1 in which the blocking means at the lower end of the spindle includes an arcuate

shaped skirt, which is rotatable by the rotation of the spindle within an annular wall of an end cap secured to the lower end of the nozzle, with said annular wall having an opening which is blocked and unblocked by said arcuate skirt.

3. The device as set forth in claim 1 in which a slidable collar closes said inlet opening.
